(57) **CLAIM**

The ornamental design for a “lid handle for an article of cookware”, as shown and described.

DESCRIPTION

FIG. 1 is a perspective view of a “lid handle for an article of cookware” showing my new design;

FIG. 2 is a top plan view thereof;

FIG. 3 is a front side elevational view thereof;

FIG. 4 is a left side elevational view thereof;

FIG. 5 is a rear elevational view thereof;

FIG. 6 is a right side elevational view thereof; and,

FIG. 7 is a bottom plan view thereof.

The “lid for article of cookware” shown in phantom lines depicts the environment of my new design and forms no part of the design of my invention.
